United States Patent Office.

ALFRED ROOKER, OF LONDON, ENGLAND.

Letters Patent No. 78,897, dated June 16, 1868; patented in England, September 25, 1867.

IMPROVEMENT IN FAUCETS.

The Schedule referred to in these Letters Patent and making part of the same.

TO ALL TO WHOM IT MAY CONCERN:

Be it known that I, ALFRED ROOKER, of East street, London, England, have invented a certain new and useful Improvement in Taps for beer-casks and other vessels; and I do hereby declare the following to be a true, full, and exact description thereof, reference being had to the annexed drawings, and to the figures and letters marked thereon; that is to say—

Figure 1 is a side view, partly in section, of a beer-tap constructed according to my invention, and applied to the tap-hole of a cask.

Figure 2 is a side view, partly in section, of a modification of fig. 1.

Figure 3 shows a tap suitable for drawing off liquids from champagne and other bottles.

The chief object of my invention, in so far as it relates to taps for casks, is to avoid the necessity of driving in, by means of the tap itself, the bung or cork which closes the tap-hole of the cask; and my improvement consists in constructing the inner end of the stem of the tap hollow, and with an annular cutting-edge, so that it will cut out a cylindrical piece of the bung or cork, and at the same time close the aperture thereby formed in the bung.

A, fig. 1, is the stem of the tap, which is formed with the usual holes *a* to allow the beer or liquid to enter the stem. The inner end *B* of the stem has a cutting-edge, *b*, for the purpose before explained, and is hollow, as shown, to receive the cylinder of cork, as cut by the cutting-edge. *C* is a stop in the stem, to prevent the cylinder of cork reaching and closing the holes *a*. This stop may sometimes be dispensed with.

The action is as follows: When it is required to tap a cask, the cutting-edge *b* is forcibly pressed against the cork, *D*, while the tap is made to rotate until the edge *b* has cut through the cork. The cylinder of cork thus removed is received in the portion *B* of the stem. The tap is then pushed in until the holes *a* reach the inside of the cask. The tap may be fitted with an ordinary key, and formed with a vent-aperture. The cutting-edge *b* may, if desired, be made of or faced with steel, and in that case it may be used to form a hole for the tap in the wood of the cask. When the tap is removed from the cask, the cylinder of cork may be extracted from the part *B* by a cork-screw, or otherwise.

In the modification shown in fig. 2, the cutting-edge is made saw-toothed or serrated.

The tap shown in fig. 3 is constructed in the same manner as that shown in fig. 1, but is made sufficiently narrow to be passed through the cork of a bottle, as shown, to allow the contents to be drawn off. *C* is a hole, to admit an appliance to push out the cork-cylinder from the end of the stem, when required.

What I claim, and desire to secure by Letters Patent, is—

1. The annular cutting-edge *b* and the hollow part *B*, applied to a tap having perforations therein, and acting substantially as herein described.

2. The cutting-edge *b* of the hollow part *B* of the stem, which receives the excised plug, in combination with the stop *C*, all substantially as and for the purpose herein set forth.

In witness whereof, I, the said ALFRED ROOKER, have hereunto set my hand; this twelfth day of December, one thousand eight hundred and sixty-seven.

ALFRED ROOKER.
